DETACHABLE MARKING TAG

Nathan I. Fleischer, Cincinnati, Ohio, assignor
to The Fleischer Mills, Inc., Cincinnati, Ohio,
a corporation of Ohio

Application March 2, 1949, Serial No. 79,248

3 Claims. (Cl. 40—20)

1

This invention relates to marking tags.

An object of the invention is to provide a marking tag which includes an integral open ended attachment pocket into which the edge of an article to be identified is receivable for locating the body portion of the tag in a definite, predetermined relationship with said article.

Another object of the invention is to provide a marking tag, one end of which is twice folded over upon itself to provide an open ended attachment pocket into which the edge of an article to be identified may be received and then secured by means of a wire staple passing through said tag, pocket and article.

Still another object of the invention is to provide a marking tag having the hereinabove described characteristics which is so constructed and arranged as to be quickly and cleanly detached from the identified article in response to the application of sudden pull on the body portion of the tag.

A further object of the invention is to provide a marking tag fabricated from a sheet of material folded whereby to effect an automatic opening and withdrawal of a wire staple passed therethrough for securing the tag to an article to be identified in response to a deliberate endwise pull on said tag.

Still a further object of the invention is to provide a marking tag having the hereinabove described characteristics which is adapted to be secured to an article to be identified by means of a wire staple which will be opened and cleanly withdrawn through said article incident to a sharp endwise pull on said tag.

Another object of the invention is to provide a marking tag which is delivered to the user thereof in a pre-pleated, ready-to-attach condition, thereby facilitating its ease of attachment to an article to be identified.

Still another object of the invention is to provide such a marking tag which may be quickly and securely attached to an article to be identified by means of a wire staple, said tag being quickly and easily removed from the article in response to a deliberate endwise pull.

Another object of the invention is to provide a marking tag which includes an integrally formed open ended attachment pocket into which the edge of an article to be identified may be received, wherein the outer portions of the sides of said pocket comprise tabs which may be, if desired, manually grasped for effecting a disengagement of said tag from the article.

A further object of the invention is to provide

2

a marking tag having the hereinabove described characteristics which may be secured to an article to be identified by means of a wire staple passing thru the three plies of the tag and thru the article to be identified, wherein opposite portions of said staple will be disposed in overlapping relationship with the outer faces of the outermost of said three plies, and wherein those portions of said plies disposed above said staple remote from the edge of the article identified, comprise a pair of tabs which may, if desired, be grasped for simultaneously separating said tabs, straightening and then cleanly withdrawing portions of said staple thru the article without injury or damage to the article.

Still another object of the invention is to provide a marking tag having the hereinabove described characteristics which may be delivered to the ultimate user in a folded pre-pleated ready-to-use condition, said tags being provided individually, in booklets or in continuous roll form.

A further object of the invention is to provide such a marking tag which may be inexpensively produced using modern mass production methods.

These and other objects are attained by the means described herein and as disclosed in the accompanying drawings, in which:

Fig. 1 is a plan view of a strip of separable marking tags embodying the teachings of the present invention.

Fig. 2 is an edge view of a tag of Fig. 1.

Fig. 3 is a plan view of an article to be identified provided with three tags of the present invention secured thereto in different positions.

Fig. 4 is a sectional view taken on line 4—4 of Fig. 3.

Fig. 5 is a sectional view taken on line 5—5 of Fig. 3.

Fig. 6 is a sectional view taken on line 6—6 of Fig. 3.

Fig. 7 is a view similar to Fig. 4 but showing a step in the process of detaching a tag from an article.

Fig. 8 is a view similar to Fig. 7 showing a later step or sequence of the tag-removing, fastener-withdrawing operation.

Fig. 9 is a view similar to Fig. 5 illustrating the preferred mode of removing the marking tag from the article identified.

Fig. 10 is a sectional view illustrating the relationship of the various plies of the tag, the article being identified and the tag securing staple when in a closed, tag securing condition.

Fig. 11 is a view similar to Fig. 10 but showing a step in the process of removing the staple.

With reference now to Fig. 2, the numeral 10 indicates generally the body portion of a tag, the upper end of which has been folded upon itself as at 12 and then back on itself as at 14 to provide a substantially U-shaped open ended pocket portion defined by legs or panels 12 and 14, which collectively comprise a tuck or pair of mounting panels.

In the preferred embodiment of the invention, the tag may be fabricated from a strip of wet-strength paper, fabric, or from any other suitable sheet-like substance which will withstand the deleterious and disintegrating forces inherent in modern laundry and dry cleaning operations; or the tag may be fabricated from less durable material when to be used for marking items of merchandise.

In the preferred embodiment of the invention, suitable indicia, see Figs. 1 and 3, may be provided on one or both faces of body portion 10, or suitable indicia may be provided on body portion 10 prior to, or just after a tag has been secured to an article to be identified.

With reference now to Figs. 3 and 5, it will be observed that a tag may be attached to an article to be identified, denoted generally by the numeral 20, by inserting an edge of said article in the open ended pocket defined by legs or panels 12 and 14, after which the tag may be securely though releasably secured to the article by fastening means 22, which may, if desired, comprise a wire staple, the legs 23 of which pass through all three plies of the tag and article 20 and are then turned over in overlapping relationship with outer face 26 of panel 14, see Fig. 10. Intermediate portion 25 of the staple overlies outer face 24 of body portion 10 of the tag. It will be noted that legs 23 of the staple engage the single ply of the tag, whereas the intermediate portion 25 overlies the outer face of the two or double ply side of the tag.

With particular reference now to Figs. 9 and 11, it will be observed that the tag has been so constructed and arranged as to effect its clean detachment from article 20 in response to a sharp endwise pull P applied to body portion 10. The double ply beneath intermediate portion 25 of the staple effectively precludes this portion from tearing through the tag with the result that the overturned legs 23 are straightened whereby to facilitate their withdrawal through outer ply 14 of the tag and thence through article 20 for cleanly removing the tag and staple.

A tag constructed in accordance with the teachings of the present invention may be secured to the finest and sheerest of fabrics and removed therefrom by a pull applied to the body portion of the tag without tearing, snagging or in any way injuring the fabric.

It should be observed that a tag having been secured to the article to be identified by means of a staple, will not become accidentally or unintentionally detached, since it requires a positive, deliberate, pull on the tag body to effect its release.

As disclosed in Figs. 4, 7 and 8, the fastening means is disposed intermediate the length dimension of the U-shaped attachment portion, whereby those portions disposed beyond the fastener means, remote from body portion 10 comprise a pair of tab portions 28 and 30 which, as disclosed in Figs. 7 and 8 may be grasped for effecting an alternate method of separation of

the tabs and for simultaneously effecting a release and clean withdrawal of the fastening means from the article. In those instances where the fastening means comprise a staple 22, the free legs thereof will be straightened incident to a separation of tabs 28 and 30, thereby facilitating a clean withdrawal of the ends of the staple thru the article identified, without injury or damage to it. It should be noted that as before, the staple will be removed along with the tag, being completely withdrawn from the article. After thus being removed from the article, the tag, being quite inexpensive, may be discarded.

If desired, the tag may be secured to article 20 in the manner disclosed in Fig. 4, wherein the other side or face of body portion 10 is disposed outermost from that disclosed in Fig. 5, and wherein two plies 10 and 12 of the material are disposed under the folded free ends of attaching staple 22 whereas but one ply 14 is disposed under the head or intermediate portions of the staple.

In Fig. 6, the marking tag has been applied to article 20 in such a manner as to dispose body portion 10 within the confines of said article, and in overlapping relationship therewith. This is in sharp contrast to the manner in which the tags of Figs. 4 and 5 have been attached to the article, wherein the body portion of said tags projects or extends outwardly from edge 42 of the article. However, it will be noted that the tag of Fig. 6 may be detached from article 20 in a manner similar to that illustrated in Figs. 7 and 8 but wherein the tab portions grasped to effect a removal will comprise portions 44 and 46.

While I have disclosed and prefer to use a staple as a fastening means, it should be understood that, if desired, stitching may be resorted to, said tag functioning in the same manner so far as effecting a removal of the stitches is concerned as when a staple is utilized as the fastening media.

If desired, marking tags embodying the teachings of the present invention may be provided as individual, preformed pleated tags or as a series of 3, 4 or 5 wherein each tag is severable from an adjacent tag by means of suitable score line 50, or, if desired, said tags may be provided in roll form wherein adjacent tags are separable along score lines 50, see Fig. 1.

It should be understood that various changes and modifications may be made within the structural details of the device within the scope of the appended claims, without departing from the spirit of the invention.

What is claimed is:

1. A marking tag of the type adapted to be releasably secured to an article to be identified by means of stapling, which comprises a body portion one end of which is twice folded upon itself to provide a U-shaped tuck dimensioned to receive and overlappingly engage the edge of an article inserted therein, said tag secured to said article by a staple clinched through all thicknesses of said tag and through said article and with the free ends thereof bent down upon the adjacent tag surface, said tag detachable from said article incident to the application of an endwise pull applied to the body portion for separating the free outer ends of the tuck and simultaneously withdrawing said staple from said article without injury thereto.

2. A marking tag comprising a strip of ma-

material one end of which is folded downwardly and thence upwardly for providing a three ply thickness of material wherein the edge of an article to be identified is receivable between those two plies remote from the body portion of the tag for disposing one ply on one side and two plies on the other side of said article, said tag secured to said article by a U-shaped staple, the legs of which pass through all three plies of the tag and said article with the intermediate portion of the staple overlying the outer face of the two ply thickness of the tag and with the free ends of said legs disposed in overlapping relationship with the outer face of the one ply thickness, said double ply thickness constructed and arranged to withdraw said staple from the third ply and said article incident to a sharp endwise pull on the body portion of the tag.

3. A marking tag comprising a strip of material one end of which is folded downwardly and thence upwardly for providing a three ply thickness of material wherein the edge of an article to be identified is receivable between those plies

10

15

20

remote from the body portion of the tag for disposing one ply on one side and two plies on the other side of said article, said tag secured to said article by a U-shaped staple, the legs of which pass through all three plies of the tag and said article with the intermediate portion of the staple overlying the outer face of the one ply thickness of the tag and with the free ends of said legs disposed in overlapping relationship with the outer face of the two ply thickness, said double ply thickness constructed and arranged to withdraw said staple from the third ply and said article incident to a sharp endwise pull on the body portion of the tag.
